ENGINE STARTER CONTROL

Paul L. Schneider and Harold J. Cromwell, Anderson, Ind., assignors to General Motors Corporation, Detroit, Mich., a corporation of Delaware

Application May 9, 1951, Serial No. 225,425

6 Claims. (Cl. 290—38)

1

This invention relates to engine starter control apparatus by which an engine cranking electric motor is caused to operate by closing a manually controlled switch and by which operation of the motor is prevented while the engine is self-operative.

An object of the present invention is to provide improved means whereby the starting motor cannot be operated while the engine is self-operative. In the disclosed embodiment of the present invention, this object is accomplished by the use of a relay switch having a coil which is energized by closure of a manually controlled switch to effect closure of relay contacts to cause the starting motor to be connected with a current source. By means responsive to self operation of the engine the contacts are separated regardless of the energization of the coil.

Further objects and advantages of the present invention will be apparent from the following description, reference being had to the accompanying drawings, wherein a preferred embodiment of the present invention is clearly shown.

In the drawings:

Fig. 1 is a wiring diagram and a diagrammatic side view of a relay switch embodied in the present invention and shown in open position.

Fig. 2 is a fragment of the wiring diagram shown in Fig. 1 and showing the relay switch in its closed position.

Fig. 3 is a diagrammatic sectional view showing a fragment of an engine intake manifold and a suction device used with the relay switch shown in Fig. 1.

Fig. 4 is an enlarged detail sectional view of parts used in the suction device shown in Fig. 3.

Fig. 5 is an end view looking in the direction of arrow 5 of Fig. 4.

Referring to Fig. 1, a generator 10, grounded at 11, is connected by a wire 12 to a cut-out relay 13 which operates automatically to connect the generator to a battery 16 grounded at 17. The field winding 18 of the generator is connected with ground 20 through a voltage regulator 19.

The starting system for the internal combustion engine includes a starting motor 25 grounded at 26 and having a field winding 27 connected by a wire 28 to a fixed contact 29 of a switch 30. The switch 30 has a movable contact 32 normally maintained out of engagement with fixed contacts 29 and 31 by a spring 33. The fixed contact 31 is connected by a wire 34 with the storage battery 16.

The switch 30 is automatically moved into closed position by an electromagnetic means

comprising an armature 35 surrounded by a winding 36 of fewer turns of relatively coarse wire and a winding 37 of a relatively large number of turns of fine wire. One end of the winding 37 is grounded at 38 and one end of the winding 36 is connected with the wire 28 which is on the starting motor side of the starting switch 30.

The energizing circuit for the coils 37 of the electromagnetic switch 30 is completed by closing an ignition switch 40, a neutral safety switch 41, and an electromagnetic relay switch 45 including a core 46, a coil 47 surrounding the core and a frame 48 attached to a support 49. One end of the coil 47 is connected by a wire 50 to the wire 12 while the other end of the coil is connected by a wire 51 to the fixed contact 52 of the neutral safety switch 41. The frame 48 is provided with an ear 55 to which one end of a leaf spring 56 is fixed. An armature 57 is fixed to the free end of leaf spring 56 and is positioned above the core 46 and a resilient arm 58 is attached to the armature 57. The arm 58 supports a contact 59. A U-shaped bracket 60, supported by the support 49, includes arms 61 and 62. The arm 61 carries at its upper end a switch contact 63 in alignment with the contact 59 on arm 58. The arm 58 extends beyond the contact 59. When the coil 47 of the relay switch 45 is energized by closing switches 40 and 41, the magnetized core 46 attracts the armature 57 which in turn moves the arm 58 to bring the contact 59 into engagement with contact 63.

A member 65 of insulating material is pivoted on a stud or pin 66 attached to the arm 62. The member 65 has a rounded cam portion 65a located below the free end 58a of the arm 58. A friction washer 67 is disposed between the head 68 of pin 66 and the member 65. The member 65 has an elongated slot 69 to receive an end portion 70 of a link 71 to provide a lost motion connection therebetween.

The relay switch 45 and the bracket 60 are enclosed within a cup-shaped housing 72 which is secured to the support in any suitable manner. The housing 72 has a peripheral flange 73 which engages a resilient gasket 74 disposed between the flange 73 and the support 49. A side wall 75 of the housing is provided with an opening 76 through which projects the link 71.

A suction device 80 includes a container including cup-shaped shells 81 and 82. The shell 81 is provided with a tubular flange 83 which surrounds the opening 76 and is secured to the wall 75. The shells 81 and 82 are flanged at

their peripheries and are secured together by bending over the peripheral flange of shell 81 over the peripheral flange of shell 82 to clamp the periphery of a flexible diaphragm 84 between the flanges. A bushing 85 is secured at one end in a central opening provided in shell 82 and a plug 86 is threaded into the bushing 85. The plug 86 guides for longitudinal movement a sleeve 87. The plug 86 is enlarged at 88 and provides a shoulder 89. The plug is reduced in diameter at 90 to form a shoulder 91. The end of the reduced portion 90 forms a stop.

The sleeve 87 is provided with an external flange 92 which abuts the shoulder 89; and has a restricted hole 93 (Figs. 4 and 5) communicating with radial slots 94. The sleeve 87 has an external annular groove adjacent its end to receive a C-washer 95 which is housed within a cup-shaped washer 96 slidably supported on the sleeve. The washer 96 is urged against the C-washer by a relatively heavy spring 97 having one end engaging the shoulder 91 and the other end bearing against washer 96 to urge sleeve 87 to the right, as viewed in Fig. 3, to hold the flange 92 against the shoulder 89.

A relatively light spring 98 is enclosed within the suction device 80 and bears at one end against the shoulder 91 and at its opposite end against a cup-washer 99 which, together with a washer 100, is secured to the central portion of the diaphragm 84 by a rivet 102. Spring 98 yieldingly urges the diaphragm 84 away from the sleeve 87. The left end of link 71 is pivotally connected with the rivet 102.

A flexible conduit 110 is fitted over the end of the plug 86 and over one end of a pipe 111. The other end of pipe 111 is enlarged to provide a recess 112 to receive a ball check valve 113 which a spring 114 urges against a seat 115. The enlarged end of the pipe 111 is internally threaded to receive a hollow extension 116 of an intake manifold 117 of an internal combustion engine. The pipe 111 is provided with an orifice or control bleed 118 above the check valve seat 115 for the purpose of relieving vacuum in the diaphragm chamber slowly while the spring 114 urges the ball 113 against the seat 115.

When the engine is not running the spring 98 urges the diaphragm 84 to the right causing the link 71 to move member 65 about its pivot and away from under the end 58a of arm 58 so that contacts 59, normally separated as shown in Fig. 1 from contact 63 by the bias of arm 58, will be permitted to engage contact 63 when relay coil 47 is energized.

The operation of the present invention is as follows: The closure of ignition switch 40 and the neutral safety switch 41 completes a circuit through the battery 16, switches 40, 41, wire 51, coil 47, wire 50, wire 12 and generator 10 to ground 11 whereby the coil 47 is energized to attract armature 46 to close contacts 59, 63. When that happens, current will flow from the battery 16, wire 125, contacts 59 and 63, wire 126, coil 37 to ground 38 and coil 36 through motor 25 to ground 26. The energization of coils 36 and 37 closes switch 30. The starting circuit is completed thereby causing the starting motor to crank the engine.

When the engine becomes self-operative and drives the generator at such speed that generator counter-voltage opposes battery voltage impressed on relay coil 47, said coil is deenergized and contacts 59 and 63 are separated. Therefore, the operation of the starting motor

will cease if there are no other means for effecting cessation. The present invention, however, provides means for effecting discontinuance of operation of the starting motor independently of the status of the relay coil 47.

During the cranking of the engine, the suction produced in the intake manifold will be sufficient to move the diaphragm 84 to the left against the tension of the light spring 98 to compress same until the rivet 102 engages the end of sleeve 87. The diaphragm movement obtained during cranking is less than required to cause the member 65 to effect separation of the contacts 59 and 63; but this movement of the diaphragm 15 causes the link 71 to take up the lost motion between the link end 70 and the slot in the member 65. When this happens, the stiff spring 97 is not additionally compressed beyond its initial state of compression. When the engine becomes self-operative, the stiff spring 97 yields under high intake manifold suction, for example 10" Hg. As the stiff spring 97 yields, the diaphragm causes the link 71 to move the member 65 about its pivot, thereby causing the cam portion 55a to engage the end 58a of arm 58 to separate contact 59 from contact 63. This results in deenergization of coils 36 and 37 and the starting switch 30 is opened by the spring 33.

So long as the engine is self-operative, the 30 engine intake vacuum does not fall to such low value as to result in movement of member 65 from under arm end 58a. This cannot occur until intake vacuum has dropped to 1" Hg, for example; and such low value does not occur while 35 the engine is self-operative even on full load and wide open throttle.

When the engine is propelling the vehicle, the neutral safety switch 41 is open because it is under control by a transmission selecting lever L which on being moved from Neutral to Drive or Reverse causes the opening of switch 41. Therefore, coil 47 of relay 45 is deenergized. If the transmission selecting lever is moved to Neutral while the engine is running, the starting switch 30 cannot be closed because the suction device maintains separation of contacts 59 and 63.

The present invention can be used with a starting motor which is connected with the engine 50 by a starter drive which is actuated by the armature 35 of switch 30 or by a starter drive of the automatic screw-pinion type. If the screw-pinion drive is used, it is desirable, in case of a false start, to allow the starting motor to come to rest before the reclosing of contacts 59 and 63 of relay 45.

In case of a false start and the engine had momentarily produced, for example, 10" Hg, suction to cause diaphragm 84 to move left far enough to actuate the member 65 to separate the contacts 59, 63, means are provided to cause the suction in the diaphragm chamber of the device 80 to drop relatively slowly, thereby increasing the time between the false start and the reclosing 60 of the contacts 59 and 63. When the engine stops after a false start, suction in intake 117 immediately drops and check valve 113 is urged by the spring 114 against the seat 115. Air enters the bleed orifice 118 to cause suction in 65 the diaphragm chamber to decrease at a rate less than the rate of decrease in suction in the intake manifold 117. The size of the control bleed 118 is such that, after contacts 59 and 63 have separated and switch 30 has opened, reclosing of contacts 59 and 63 does not occur un- 70

til after the starting motor has stopped. Therefore a starter drive of the screw-pinion type will operate properly to connect the motor with the engine flywheel gear because the motor is at rest when the motor is connected with the battery.

The cranking motor is caused to operate by closing the ignition switch provided the transmission selecting lever is in "Neutral" or "Parking" position. The selection of any other position renders the starter inoperative. This is accomplished by use of the neutral safety switch 41 operated by the transmission selecting lever. If the engine stops while the transmission is in one of its driving positions with the ignition switch turned to "on" position, the engine is restarted merely by moving the transmission selecting lever to "Neutral" position or to the "Park" position.

The present invention can be used on a vehicle having a standard or manually operated gear shift. In such case, the switch 41 could be a manually operated dash-switch.

While the embodiment of the present invention as herein disclosed, constitutes a preferred form, it is to be understood that other forms might be adopted.

What is claimed is as follows:

1. In an engine starting system, the combination comprising, an electric starting motor; a current source; and means for effecting connection of the source and the starting motor, said means including a relay switch having a coil, a fixed contact and a movable contact; a manually controlled switch for connecting the coil with the source, said switch, when closed, causing the coil to be energized to close the contacts; a movable member to engage a support for the movable contact of the relay; and means for moving the member to separate the contacts in response to suction in the intake manifold of the engine when it is self-operative.

2. In an engine starting motor system, the combination comprising, an electric motor; a current source; an engine intake manifold; and means for effecting connection of the source and the starting motor, said means including a relay switch having a coil and cooperating contacts, one of which is movable; a manually controlled switch for connecting the coil with the source, said switch, when closed, causing the coil to be energized to close the contacts; a movable member to engage a support for the movable contact of the relay; a suction device having a chamber connected with the intake manifold and closed by a diaphragm connected with the member; a relatively weak spring opposing movement of the diaphragm; a relatively stiff spring for limiting the movement of the diaphragm by intake suction during cranking of the engine to a distance less than required to cause the member to separate the contacts, said stiff spring yielding to intake suction produced when the engine is self-operative so that the member separates the contacts.

3. In an engine starting motor system, the combination comprising, an electric motor; a current source; an engine intake manifold; and means for effecting connection of the source and the starting motor, said means including a relay switch having a coil and cooperating contacts, one of which is movable; a manually controlled switch for connecting the coil with the source, said switch, when closed, causing the coil to be energized to close the contacts; a movable

member to engage a support for the movable contact of the relay; a suction device having a chamber connected with the engine intake manifold; a diaphragm closing the chamber; means connected with the diaphragm and having a lost motion connection with the member; a relatively weak spring opposing movement of the diaphragm; a relatively stiff spring for limiting the movement of the diaphragm by intake suction during cranking of the engine to a distance less than required to cause the member to separate the contacts, said stiff spring yielding to intake suction produced when the engine is self-operative so that the member separates the contacts.

4. In an engine starting system, the combination comprising, an electric motor; a current source; an engine intake manifold; and means for effecting the connection of the source and the starting motor, said means including a relay having a coil, a fixed contact, and a movable contact; a manually controlled switch for connecting the coil with the source, said switch, when closed, causing the coil to be energized to close the contacts; a movable member to engage a support for the movable contact of the relay; a suction device having a chamber connected with the engine intake manifold; a diaphragm closing the chamber and connected with the member and operative for moving the member to separate the contacts in response to suction in the intake manifold of the engine when it is self-operative; and means operating, in case of a false start, to obtain decrease of suction in the chamber at a rate less than the rate of decrease of suction in the manifold.

5. In an engine starting system, the combination comprising, an electric starting motor; a current source; an engine intake manifold; and means for effecting the connection of the source and the starting motor, said means including a relay having a coil, a fixed contact, and a movable contact; a manually controlled switch for connecting the coil with the source, said switch, when closed, causing the coil to be energized to close the contacts; a movable member to engage a support for the movable contact of the relay; a suction device having a chamber connected with the engine intake manifold; a diaphragm closing the chamber and connected with the member and operative for moving the member to separate the contacts in response to suction in the intake manifold of the engine when it is self-operative; a conduit providing a connection between the chamber and the manifold, said conduit having a control bleed orifice; and a check which blocks connection between the intake and the chamber in case of a false start, said orifice retarding decrease of suction in the chamber whereby suction in the chamber decreases at a rate less than the rate of decrease of suction in the manifold.

6. In an engine starting system, the combination comprising, a starting motor, a current source; an engine intake manifold; means for effecting connection of the source and the starting motor, said means including a relay switch having a coil, a fixed contact and a movable contact; a manually controlled switch for connecting the coil with the source, said switch, when closed, energizing the coil to close the contacts; a movable member adapted to engage a support for the movable contact of the relay; a suction device having a chamber connected with the intake manifold; a diaphragm closing

the chamber; means connected to the diaphragm and operatively connected with the movable member; resilient means acting upon the diaphragm to limit the movement of the diaphragm by intake suction during cranking so as to prevent the member from separating the contacts, said resilient means yielding to intake suction produced when the engine is self-operative so that the member separates the contacts.
